US00D910581S

(12) **United States Design Patent** (10) **Patent No.:** **US D910,581 S**
Rummel et al. (45) **Date of Patent:** **** Feb. 16, 2021**

(54) **DISPENSING DEVICE PANEL**

(71) Applicant: **BRITA GMBH**, Taunusstein (DE)

(72) Inventors: **Christian Rummel**, Benningen (DE);
Tim Storti, Schwieberdingen (DE)

(73) Assignee: **BRITA GMBH**, Taunusstein (DE)

(**) Term: **15 Years**

(21) Appl. No.: **29/659,959**

(22) Filed: **Aug. 14, 2018**

(30) **Foreign Application Priority Data**

Feb. 26, 2018 (EM) 004725836

(51) **LOC (13) Cl.** **13-03**
